UNITED STATES PATENT OFFICE.

GARRIT VAN ROOIJEN, OF CHESTER, NEW JERSEY.

TROUSERS-STRETCHER.

1,072,881.

Specification of Letters Patent.

Patented Sept. 9, 1913.

Application filed December 19, 1912. Serial No. 737,612.

To all whom it may concern:

Be it known that I, GARRIT VAN ROOIJEN, a subject of the Queen of the Netherlands, residing at Chester, county of Morris, and 5 State of New Jersey, R. F. D. No. 1, have invented certain new and useful Improvements in Trousers-Stretchers, fully described and represented in the following specification and the accompanying drawings, forming a 10 part of the same.

The present invention relates to a stretcher adapted for insertion in the leg of a pair of trousers in contact with the fold of the trousers for the purpose of 15 preserving the folds and of stretching the wrinkles out of the cloth.

The invention comprises special features of construction including a central fulcrum-bar slotted to receive the ends of links connected with two side bars, the insertion of the links in the slots of the fulcrum-bar leaving the opposite sides of the fulcrum-bar entirely free from projections which interfere with its convenient insertion in the trousers' leg; 20 also a particular construction for the slots so as to admit the edges of the links when the stretcher is collapsed, and a particular construction of the means for expanding the side-bars and locking them in their adjusted 25 position. The links connecting the opposite ends of the side-bars to one end of the fulcrum-bar are shorter than those at the other end, to form a tapering stretcher in conformity to the legs of the trousers, and such 30 shorter links would interfere with the collapsing of the stretcher unless provision were made for a movable connection with the fulcrum-bar or the side-bars. To effect such connection, a pin-slot is made longitudinally of the fulcrum-bar transverse to the 35 slot which receives the ends of the shorter links, and the fulcrum-pin of such links is movable within such pin-slot. This permits the side-bar to change its angle automatically to conform to the taper of the trousers' 40 leg.

This fulcrum-bar is provided near one end with a special slider connected by inclined links to the two side-bars, so that the longitudinal movement of the slider operates 45 when required, to expand the side-bars within the trousers' leg, and special means is provided for locking the slider upon the fulcrum-bar to lock the side-bars when thus 50 expanded.

The invention will be understood by reference to the annexed drawing, in which—

Figure 1 is a plan of the stretcher expanded with the trousers' leg indicated by dotted lines *t*; Fig. 2 shows the stretcher collapsed; Fig. 3 is an edge view of the trousers folded with one leg *t* in section and the stretcher lying therein; Fig. 4 is a cross section on line 4—4 in Fig. 1; Fig. 5 is a cross section on line 5—5 in Fig. 1; Fig. 6 shows the broader end of the stretcher in plan; and Fig. 7 the narrower end, both views being upon a much larger scale than Fig. 1; Fig. 8 is an edge view of the slider and lock-piece.

The fulcrum-bar *a* is formed of a rectangular strip of wood having longitudinal slots *a'* and *a''*, in the plane of the stretcher, in which the inner ends of the links *b* and *c* are fitted, and their outer ends united by pivots *d* to the side-bars *e* near their ends. 75 These side-bars are shown of sheet-metal bent to form a channel of sufficient width to insert the ends of the links. The links *b* are somewhat longer than the links *c* and are jointed upon a fixed pivot *f* in the fulcrum-bar, but the pivot *g* of the links *c* is movable in a slot *h* in the fulcrum-bar so that when the side-bars are collapsed upon the fulcrum-bar, as shown in Fig. 2, the pivot moves longitudinally in the slot *h*. 80 The length of the slot *h* is proportioned to arrest the movable pivot *g* during the expansion of the side-bars, thus furnishing a rigid abutment to expand the side-bars against the 85 inside of the trousers' leg.

When the side-bars are collapsed they lie close (as shown in Fig. 2) to the fulcrum-bar, so that the entire stretcher occupies very little room and can be readily packed for 90 transportation.

The movement of the side-bars is controlled by a slider *i* fitted movably to the fulcrum-bar and connected by links *j* to the side-bars *e*. A lock-piece *k* is shown formed of wire with its ends hooked into arms upon the slider and its free end bent into a hook *k'* to engage any one of a series of holes *l* formed in the fulcrum-bar. When the side-bars are collapsed the hook of the lock-piece 95 engages the end-hole of the series. The side-bars are expanded by pushing the slider longitudinally so that the links *j* force the side-bars outwardly, and the series of holes permits the slider to be locked in different 100 positions when the side-bars are expanded. 110

with the desired tension against the inside of a pair of trousers. The links are shown as flat bars of thin metal, and the edges of the slots a' and a^2 through the fulcrum-bar 5 are formed at one end with sloping notches m , which permit the links to lie within the slots of the fulcrum-bar, as shown in Fig. 2, when the side-bars are collapsed. Only very narrow slots are required to admit the inner 10 ends of the links; thus avoiding any material weakening of the fulcrum-bar.

It has been common heretofore to pivot links in a trousers stretcher upon the exterior of the fulcrum-bar, which forms projections and shoulders upon the bar, which are very objectionable when inserting the stretcher within the leg of a pair of trousers, and it will be observed that my fulcrum-bar is free from any such projections, by reason 20 of the slots a' and a^2 which receive the ends of the links b and c , and thus leave both the opposite sides of the fulcrum-bar entirely smooth where they lie upon the cloth during the insertion of the stretcher in the trousers' 25 leg. In my construction, the only projection upon the fulcrum-bar is formed by the slider i which it will be observed in Fig. 1 is a considerable distance beyond the more widely expanded ends of the side-bars and is 30 not inserted within the leg of the trousers.

It will be understood that one of the stretchers is required for each leg of a pair of trousers, Fig. 3 showing the trousers folded with the upper leg t' cut away to expose the stretcher lying therein, and the other leg t' concealing the stretcher excepting its extreme ends.

The trousers are shown very flat in Fig. 3 with the crotch indicating the separation between the trousers' legs.

The upper end of the fulcrum-bar is provided with an eye n by which the two

stretchers with the trousers stretched thereon may hang upon a nail or hook while the trousers are being stretched.

It will be observed that the slotted form or the fulcrum-bar, which permits the employment of the slots a' and a^2 transverse to one another, is readily effected by using a square bar of wood, over which the slider 50 moves more smoothly than over an unfinished bar of iron.

The slider is shown in Figs. 4 and 5 made of two pieces of flat bar-iron to fit, each, around one side of the bar a , and having 55 arms v which are perforated for the pivots of the links j , which pivots connect the two halves of the slider together upon the fulcrum-bar. This construction is very cheap and convenient, and the lock-piece k is 60 cheaply jointed thereto by hooks upon its ends inserted through holes in the arms v , as shown in Figs. 6 and 8.

Having thus set forth the nature of the invention what is claimed herein is:

In a trousers' stretcher, the combination, with a central fulcrum-bar and the side-bars e connected thereto by the links b and c , of the slider i fitted upon the fulcrum-bar and having arms v projected at opposite sides of the same, and links j connecting the ends of the arms with the ends of the side-bars e , and the lock-piece k jointed upon both the said arms and having the hook k' , and the bar a having the series of holes l to admit 70 the hook and lock the stretcher when adjusted in the trousers.

In testimony whereof I have hereunto set my hand in the presence of two subscribing witnesses.

GARRIT VAN ROOIJEN.

Witnesses:

JAMES NAUGHTON,
ISAAC R. ROWE.
